UNITED STATES PATENT OFFICE.

TIMOTHY DRISCOLL, OF LONDON, ENGLAND.

GRAMOPHONE.

Application filed April 20, 1922. Serial No. 555,667.

To all whom it may concern:

Be it known that I, TIMOTHY DRISCOLL, a subject of the King of Great Britain, residing at London, England, have invented certain new and useful Improvements in Gramophones, of which the following is a specification.

My invention relates to gramophones.

In a gramophone fitted with an all-wood tone-arm, for example, owing to the small vertical lift of the tone-arm difficulty is experienced if the insertion or removal of the needles is attempted without rotating the sound box, while the finger of the operator is liable to be pricked during the operation. If the sound box is rotated to facilitate the insertion of the needles, its position is required to be adjusted after each insertion, so that the needle lies at the correct angle to the record.

The object of my invention is to provide an improved arrangement of tone-arm and sound box suitable for the above and other types of gramophones, in which the above disadvantages are obviated, and the replacement of the needles is effected in a simple and expeditious manner.

My invention consists in an arrangement of sound box and tone-arm in which one of these parts may be rotated relatively to the other, for the insertion or removal of needles, means being provided for automatically registering and locking the parts in the operative position.

My invention further consists in a connection, union or the like adapted to be secured to the tone-arm and having a rotatably mounted member adapted to carry the sound box, means being provided for automatically locking the rotatable member in one or more positions.

My invention also consists in the improved arrangement of tone-arm and sound box, and connection therefor, to be hereinafter described.

Figure 1 shows an elevation of a tone arm and sound box for a gramophone provided with my invention.

Figure 2 shows an elevation on an enlarged scale of the connection between the tone-arm and sound-box, while

Figure 3 shows a longitudinal section of the same.

Figure 4 shows a cross section of the con-

nection, the section being taken on the line IV—IV Figure 3.

Figures 5, 6 and 7 show elevations of the parts forming the connection.

In carrying my invention into effect according to one form and as applied by way of example to a gramophone provided with a tone-arm of the all-wood type, I attach to the sound box end of the tone-arm 1, Figure 1, a ring 2 of brass or other suitable material. This ring is provided at its rear end with a recess or groove 3, Figure 3, into which the end of the tone-arm 1 fits, while the forward end of the ring 2, is of reduced diameter to accommodate an externally disposed split spring-ring 4, Figures 2, 3, 4 and 6.

In the reduced portion two holes 5 and 6, Figures 3, 4 and 5 are formed into which balls 7 and 8 respectively are inserted. These balls are adapted to be retained in position by the spring-ring 4, in such a manner, that a portion of the balls project beyond the inner periphery of the ring 2. Within the ring 2 an annular member 9, Figures 3, 4 and 7, having an external flange 10 on its outer end, is rotatably mounted.

On the outer periphery of the annular member, a circumferential groove 11 is formed having a spherical depression or hole 12 at one point. The groove 11 registers with the balls 7 and 8, when the annular member 9 is inserted in the ring 2.

A hole 13 is formed and threaded through the flange 8 of the annular member 7, and has a screw 14 inserted therein, for screwing the sound box 15, in the annular member.

In assembling the parts the spring-ring 4 is rotated until one of the holes, for example the hole 5, registers with the split in the spring-ring. The annular member 9 is then inserted in the ring 2 and the ball 7 inserted into the hole 5. The spring-ring 4 is then rotated until the split registers with the hole 6 when the ball 8 is inserted and the spring-ring rotated so that both the balls are pressed into the groove 11.

The holes 5 and 6 are spaced apart to correspond to the operative and upturned positions of the needle holder 16, as shown in Figure 1.

The annular member 9 may be easily rotated except when either of the balls 7 and 8

register with the spherical depression or hole 12, in which positions a considerable force must be exerted to rotate the annular member 9, past these points so that in these 5 positions it is practically locked.

The sound box 15 is secured in the annular member 9 by means of the screw 14 before described, and in such a position that when the needle is in the operative position, 10 the ball 7 registers with the depression or hole 12 in the groove 11, of the annular member 9.

When it is desired to change the needle, the sound box 15 and the attached annular 15 member 9, are rotated until the ball registers with the depression or hole 12 when the holder for the needle is in a more or less upright position shown in dotted lines on Figure 1. The needle is then inserted and the 20 sound box 15 rotated in the reverse direction, until the ball 7 springs into the depression or hole 12 and locks the sound box in the operative position of the needle.

In some cases I may dispense with one of 25 the balls above described and arrange the ring 2 with a single ball which locks the annular member in the operative position, of the needle only, or I may use one ball in conjunction with two depressions spaced apart 30 on the annular member so as to lock the sound box in the operative and upturned position of the needle holder.

By means of my invention it will be seen that needles may be inserted or removed in a very convenient and simple manner, while the sound box is automatically registered and locked whenever the operative position has been reached in its rotation. 35

I wish it to be understood that the above example of my invention is simply to be regarded as typical only, and not as in any way limiting my invention thereto, as modifications may be made therein without departing beyond the scope of my invention. 40

I claim:

A tone arm having a circumferentially reduced extremity formed with an opening therethrough, a sound box carrying member rotatably mounted in said extremity and having an annular groove with which said opening is in registry, a ball loosely seated in said opening and riding in said groove, said member having an opening within the groove to receive the ball in a certain relative position of the member and tone arm, 50 and a spring band slidably fitting said extremity and overlying and bearing on said ball, the ends of said band being spaced apart to permit insertion or withdrawal of said ball at will. 55

In testimony whereof I have signed my name to this specification. 60

TIMOTHY DRISCOLL.
